UNITED STATES PATENT OFFICE.

THOMAS D. FINIZIO, OF KITCHAWAN, NEW YORK, ASSIGNOR TO STEATITE ELECTRIC PRODUCTS CORPORATION, A CORPORATION OF NEW YORK.

ELECTRIC IRON.

1,395,635.

Specification of Letters Patent.

Patented Nov. 1, 1921.

Application filed April 16, 1920. Serial No. 374,495.

To all whom it may concern:

Be it known that I, THOMAS D. FINIZIO, a citizen of the United States, residing at Kitchawan, Westchester county, in the State 5 of New York, have invented certain new and useful Improvements in Electric Irons, of which the following is a full, clear, and exact specification.

My invention relates to improvements in 10 electric irons, and the same has for its object more particularly to provide a simple, efficient and reliable device which is composed of the fewest parts possible, and which is not liable to get out of order.

15 Further said invention has for its object to provide an electric iron in which the heating medium is constructed as a single unit which may be readily inserted into or removed from the iron without necessitating 20 the making of any electric connections.

Further said invention has for its object to provide an electric iron in which the heating element is composed essentially of two parts, namely; a heat producing medium 25 and a heat emitting medium joined together as a single unit.

Further said invention has for its object to provide an electric iron in which the heating medium is composed of a soapstone 30 slab having an electrical resistance element embedded therein, and the ends of said resistance secured to terminals arranged upon said soapstone slab.

Further said invention has for its object 35 to provide an electric iron having a combined attaching plug guard and iron support formed as a single structure, and secured to the iron.

Other objects will in part be obvious, and 40 in part be pointed out hereinafter.

To the attainment of the aforesaid objects and ends my invention consists in the novel details of construction, and in the combination, connection and arrangement of parts 45 hereinafter more fully described and then pointed out in the claims.

In the accompanying drawings forming part of this specification wherein like numerals of reference indicate like parts:

50 Figure 1 is a side elevation showing one form of electric iron constructed according to and embodying my said invention;

Fig. 2 is a side elevation partly in section on the line 2—2 of Fig. 7, showing the con-

struction and arrangement of the heating 55 medium;

Fig. 3 is a detail inverted plan view of the heating medium detached from the iron;

Fig. 4 is a rear end view of the iron, and

Fig. 5 is a detail perspective view showing 60 the construction of the combined attaching plug guard and iron support.

In said drawings 10 designates a plate formed of cast iron, having the contour of a usual iron, upon which is disposed a comparatively thick slab of soapstone 11 which is conformed in outline to said plate 10 and secured thereto by screws 12, 12 which extend through the handle bail 13, and through said soapstone slab 11, and into the plate 10. 70 The handle guard 13 is provided at its upper ends with a handle 14 which is secured intermediate the ends of the handle bail by a screw 15.

The heating element comprising the soapstone slab 11 is provided in its underside with a recess 11^a, preferably as shown at Fig. 3, and within said recess is secured by a suitable cement 11^b a coil of resistance wire 16 having its ends 17, 18 secured to inclined 75 terminals 17', 18' extending from the upper side of said soapstone slab downwardly into the same and provided at their inner ends with nuts 19, 19 whereby the ends of the terminals 17, 18 may be secured to said contacts 17', 18'.

20 denotes a cover preferably stamped out of sheet metal and conforming in outline substantially to the plate 10 and the soapstone slab 11, and secured in position over 80 said soapstone slab 11 by the attaching screws 12, 12. The cover 20 is preferably made slightly larger in outline than the heating member 11 in order to leave an air space entirely surrounding the same, and 85 along its lower edge said cover 20 is provided at suitable intervals with apertures 21. In order to insure the circulation of air between said cover 20 and said heating medium, said cover may be provided at its 100 upper side with one or more apertures or openings 22.

23 denotes a combined attaching plug guard and iron support which is preferably made of sheet metal and formed as a unitary 105 structure, comprising a transverse member 24, of substantially U-shaped cross-section forming one part of the support for the

iron. About midway between the ends of said transverse member extends outwardly an inclined portion or web 25 provided at its opposite ends with inwardly extending 5 clips 26. The upper end of said inclined portion extends outwardly and then inwardly again, at substantially right-angles to the inclined portion 25, to form a rounded member 27 serving as the other part of the support 10 for the iron. The inwardly extending portion 28 of said support is made considerably wider than the said support and is provided with a transverse opening 29 to receive an attaching plug, and from the 15 edge of said portion 28, opposite to the rounded member 27, extends upwardly a member 30 having a threaded aperture therein to receive the end of the screw 15 which passes through the handle 14, and 20 serves to secure the same to the handle bail. At the inner edge of the support 24 are provided inwardly and downwardly extending 25 projections 31 which are adapted to be received by recesses 32 provided in the upper surface of the plate 10 adjacent to its rear edge whereby the flat horizontal portion of the heel 24 of the member 23 will be held in position intermediate the underside of the soapstone slab 11 and the upper surface of 30 the plate 10.

In order to operate the iron it merely becomes necessary to insert an attaching plug, which is suitably connected with a source of electric energy, through the opening 28 in 35 the member 23, and cause the contacts therein to engage the terminals 17', 18' extending from the upper side of the soapstone slab 11. When the plug is in proper engagement with the terminals 17', 18', and positioned 40 within the member or guard 23 the sides thereof will be held intermediate the inwardly extending clips 26, and thereby prevent any lateral movement of the plug which might result in the injury to the plug from 45 the terminals 17 and 18 secured in the soapstone slab 11.

It is to be noted particularly that by means of my construction the heating member comprising the soapstone slab 11 and the 50 resistance element embedded therein, whose ends are connected to the terminals 17', 18', the said heating member may be inserted into or removed from the iron as a unit without requiring the making of any electrical 55 connections to render the same operative. The several parts of the iron being held together and in place by means of the screws 12, 12 and 15.

Having thus described my said invention what I claim by Letters Patent is:

1. An electric iron comprising a base plate, a heating member formed as a unitary structure comprising a heat absorbing element, a heat emitting element, and means 65 carried by said absorbing element for con-

necting said heat emitting element with a source of electric energy, a handle, and means for securing said base plate, heating element and handle together, substantially as specified. 70

2. An electric iron comprising a base plate, a heating member formed as a unitary structure comprising a heat absorbing element, a heat emitting element, and means carried by said absorbing element for connecting said heat emitting element with a source of electric energy, a cover, a handle, and means for securing said base plate, heating element, cover and handle together, 75 substantially as specified. 80

3. An electric iron comprising a base plate, a heating member formed as a unitary structure comprising a heat absorbing element, a heat emitting element embedded therein, and contact members on said heat 85 absorbing element for connecting said heat emitting element with a source of electric energy, a handle, and means for securing said base plate, heating element and handle together, substantially as specified. 90

4. An electric iron comprising a base plate, a heating member formed as a unitary structure comprising an electric non-conducting heat absorbing element, an electric heating element associated therewith 95 and contact members secured in said heat absorbing element and connected to said electric heating element, a handle, and means for securing said base plate, heating element and handle together, substantially 100 as specified. 100

5. An electric iron comprising a base plate, a heating member formed as a unitary structure comprising a soap-stone element, an electric resistance element embedded therein and contact members secured to said support and connected to said electric resistance element, a handle, and means for securing said base plate, heating element and handle together, substantially as specified. 110

6. In an apparatus of the character described, a heating member formed as a unitary structure comprising a heat absorbing element, a heat emitting element, and means carried by said heat absorbing element for connecting said heat emitting element with a source of electric energy, substantially as specified. 115

7. In an apparatus of the character described, a heating member formed as a unitary structure comprising a heat absorbing element, a heat emitting element embedded therein, and contact members on said heat absorbing element for connecting said heat emitting element with a source of electric 120 energy, substantially as specified. 125

8. In an apparatus of the character described, a heating member formed as a unitary structure comprising a heat absorbing element having a recess therein, an electric 130

- heating element disposed within said recess, and contact members secured to said heat absorbing member and connected to said electric heating element, substantially as 5 specified.
9. In an apparatus of the character described, a heating member formed as a unitary structure comprising an electric non-conducting, heat absorbing element, an electric heating element associated therewith, and contact members secured in said heat absorbing element and connected to said electric heating element, substantially as specified.
10. In an apparatus of the character described, a heating member formed as a unitary structure comprising a soap-stone element, an electric heating element embedded therein, and contact members secured in said soap-stone element and connected to said electric heating element, substantially as specified.
15. 10. In an apparatus of the character described, a heating member formed as a unitary structure comprising a soap-stone element having a recess therein, an electric resistance element embedded therein, and contact members secured in said soap-stone element having their inner ends connected 20 to said electric resistance element, and having their outer ends adapted for connection
- with a source of electric energy, substantially as specified.
12. In an electric iron, a combined iron support and attaching plug guard formed of 35 a single piece comprising a pair of transverse members united by a web; one of said members having an opening therein to receive an attaching plug, attaching means extending from said transverse members, 40 and clips extending from the opposite edges of said web adapted to engage said attaching plug, substantially as specified.
13. In an electric iron, a combined iron support and attaching plug guard formed 45 of a single piece comprising a pair of transverse members united by a web; one of said members having an opening therein to receive an attaching plug, attaching means extending from said transverse members, and 50 clips extending from the opposite edges of said web adapted to engage said attaching plug at its opposite sides, substantially as specified.
- Signed at the city of New York, borough 55 of Manhattan, New York county, in the State of New York, this 8th day of April, one thousand nine hundred and twenty.
